UNITED STATES PATENT OFFICE.

WILLIS F. CORNELL, OF ALAMEDA, CALIFORNIA.

DESIGN FOR A FONT OF TYPE.

SPECIFICATION forming part of Design No. 26,310, dated November 17, 1896.

Application filed September 30, 1896. Serial No. 607,505. Term of patent 7 years.

To all whom it may concern:

Be it known that I, WILLIS F. CORNELL, a citizen of the United States, residing at Alameda, in the county of Alameda, State of California, have invented and produced a new and original Design for a Font of Type, of which the following is a specification, reference being had to the accompanying drawing.

The figure represents a font of type, including the large and small letters and the numbers.

The leading and essential feature of my design consists in the heavier shading A, which forms the complete boundary of the tint B, constituting the body of the character. This boundary-shading of said body-tint gives to the character a raised and solid appearance, which is the object in view.

Another feature of my design consists of the curl C given to an extremity of the character, said curl overlapping and projecting into the body adjacent.

The design in its entirety herein illustrated and described gives what may be termed an "imitation lithographic work."

What I claim is—

The design for a font of type substantially as herein described and shown.

In witness whereof I have hereunto set my hand.

WILLIS F. CORNELL.
